UNITED STATES PATENT OFFICE.

CHARLES SEEGER, OF PHILADELPHIA, PENNSYLVANIA.

DESIGN FOR EYEGLASS-CASES.

Specification forming part of Design No. **11,242**, dated June 10, 1879; application filed May 13, 1879.
[Term of patent 7 years.]

To all whom it may concern:

Be it known that I, CHARLES SEEGER, of Philadelphia, in the county of Philadelphia and State of Pennsylvania, have invented certain new and useful Design for Eyeglass-Cases; and I do hereby declare the following to be a full, clear, and exact description of the invention, such as will enable others skilled in the art to which it pertains to make and use it, reference being had to the accompanying drawing, which forms part of this specification, and in which is shown a side view of my design.

My design consists in an eyeglass-case having a longitudinally curved or segmental shape, with flat sides, concentric edges, and a semicircular or rounded bottom, as shown in the accompanying drawing.

The design is appropriate for cases adapted to receive open glasses.

When made of proper material and suitably embossed or otherwise ornamented, the eyeglass-case forms an attractive pendant, in keeping with the fan-cases, pockets, and other fanciful appendages of fashionable apparel.

What I claim as my invention is—

The curvilinear or segmental form shown and described, as a design for eyeglass-cases.

In testimony that I claim the foregoing I have hereunto set my hand this 9th day of May, 1879.

CHARLES SEEGER.
